TO CURTISS AEROPLANE AND MOTOR CORPORATION, A CORPORATION OF NEW YORK.

RADIATOR FOR AEROPLANES.

1,296,790.

Specification of Letters Patent. Patented Mar. 11, 1919.

Application filed November 16, 1917. Serial No. 202,428.

To all whom it may concern:

Be it known that we, WILLIAM L. GILMORE and WILLIAM E. VALK, Jr., citizens of the United States, residing at Buffalo, in the county of Erie and State of New York, have invented certain new and useful Improvements in Radiators for Aeroplanes, of which the following is a specification.

Our invention relates to radiators for propelling power plants and more particularly to radiators for water cooled aeronautical motors of the internal combustion type.

It has been the practice heretofore in the design of an aeroplane to locate the radiator of the propelling power plant either at the extreme forward end of the fuselage or at the sides thereof, or possibly directly beneath the supporting surface or surfaces according to whether the craft is of the pusher or tractor type. If the radiator is located at the nose end of the fuselage (the conventional location) all possibility of obtaining a good streamline is eliminated. For a good streamline the entering portion of any body must be rounded and blunt. If it is located elsewhere either the streamline of the fuselage is interrupted or the radiator itself set apart in the direct line of air rush. Since it is impracticable to streamline a radiator in its present form, its resistance to forward flight is enormous. The one big advantage of the present types of radiators is the dependable and efficient cooling effect afforded upon the cooling agent by reason of the direct exposure of the radiator cells or sections to the air.

The characteristic of this invention is the construction of the radiator in such manner that it is translated through the air edge-wise and with a minimum of resistance. The radiator is itself of substantially aerofoil section and mounted either within or in direct continuation of the supporting surface or surfaces. It comprises in its preferred embodiment a plurality of longitudinally extending radiator sections having spacers mounted between them to provide air passages whereby the radiating surface of the radiator is increased. Headers are mounted at the ends of the radiator sections and are connected with the motor by suitable connections. An expansion tank may or may not be provided. The construction of the radiator in aerofoil form is distinctly advantageous in that a certain amount of

lift is obtained by reason of its placement within or in continuation of the wings. Moreover, the standard wing section is such that that portion of the radiator of maximum depth or thickness lies substantially coincident with the center of lift of the wings.

Another characteristic of the invention is the use of a shutter or slide beneath the radiator to increase or diminish the effective area thereof should occasion demand. It is a known fact that in high altitudes the cooling efficiency of a radiator is increased to such an extent as to oftentimes cause the motor to stall. With this adjustable slide or shutter such a contingency is avoided. As the machine climbs the effective area of the radiator may be decreased so that the temperature of the cooling agent is held more or less constant. Furthermore, as the effective area of the radiator is decreased the total wing surface is proportionately increased and the lift augmented. The details of the invention such as the construction of the various radiator parts will be herein-after more particularly pointed out.

Of the drawings:

Figure 1, is a front end elevation of a portion of the upper supporting surface of a biplane showing its preferred location with respect to the fuselage or body and the relative location of the radiator.

Fig. 2, is a longitudinal sectional view showing the radiator construction and its arrangement between the wing beams of the supporting surface.

Fig. 3, is a plan view showing that portion of one of the supporting surfaces within which the radiator is inclosed; and

Figs. 4 and 5, are fragmentary sectional views showing details of the radiator construction.

In the embodiment of the invention selected for illustration the numeral 10 designates the fuselage or body of an aeroplane of the biplane type although but a single supporting surface (the upper) is shown. This supporting surface extends intermediate across the body 10 and is preferably of a standard construction or rather curvature in cross section. It comprises the usual front wing beam 11, rear wing beam 12, nose strip 13, trailing edge strip 14 and ribs 15, the latter being preferably alined between the nose strip and the front wing beam, the

- two wing beams, and the rear wing beam and the trailing edge strip respectively. The radiator designated as an entirety by the numeral 16 is preferably constructed in 5 duplicate radiator units arranged respectively symmetrically at opposite sides of the longitudinal vertical plane of the fore and aft axis of the machine. These sections or units are interconnected as at 17' and connected with the motor (not shown) by suitable piping or other connections. Each 10 radiator unit comprises a plurality of parallel radiator sections 17 of substantially aerofoil form. These sections are spaced apart 15 uniformly by partitions or spacers 18 which are inclined preferably rearwardly and upwardly from the underneath surface of the radiator. The radiator sections are further provided with transverse air passages 19 which lighten them and increase their radiating surface. Headers 20 are mounted at 20 the ends of the radiator units and are fastened in any suitable manner to the wing beams 11 and 12. The radiator sections 17 25 are of a duplicate construction and so related to the wing or supporting surface as to constitute in effect an integral part thereof. The connection 17' between the radiator units are inclosed within the wing structure 30 as are the radiator units themselves. The arrangement of the radiator units is accordingly such as to offer a minimum of resistance and at the same time some if not considerable lift by reason of the aerofoil form 35 given the sections of which the radiator units are composed. We thus convert into an element affording useful lift that which heretofore has offered resistance only. The radiator by its placement is translated 40 through the air edgewise and effectually streamlined. The section of the radiator of maximum thickness (which is in continuation of the corresponding section of the supporting surface) is also approximately 45 aligned with the normal center of pressure or lift. This arrangement is desirable in that a maximum of air is brought into contact with that portion of the radiator of maximum radiation surface.
- 50 As an element of safety the radiator is provided with an expansion tank 22 of streamline form. This tank is mounted preferably above the plane of the wing surface and connected as at 23 with the headers 55 20. Expansion of the cooling agent is thus taken care of should it reach a boiling point or its temperature be increased sufficiently to cause the agent to expand. The tank 22 is equipped with a filler plug 24.
- 60 The spacers 18 it will be noted are inclined in the direction of the air flow caused by the partial elimination of the air pressure ordinarily created beneath an aerofoil surface. This is desirable in that the resistance is to 65 some extent reduced. The spacers are pref-

erably constructed of thin sheet metal, flanged as at 25 and 26 and brazed on to the side walls of the radiator sections 17. The details of the spacer construction will be seen in Figs. 4 and 5. The headers 20 are of 70 course, open to the several radiator sections to provide for circulation of the cooling agent from the forward end of the radiator rearwardly to the sections to the outlet end at the rear.

By the placement of the radiator units at opposite sides of the fore and aft axis of the machine and in close proximity to the fuselage, the formation of air pockets beneath the wings adjacent the fuselage is to some extent eliminated as the air which would otherwise be confined at this point is permitted to flow through the air passages formed between the radiator sections.

Each unit of the radiator is further provided with a shutter or slide 27 movable longitudinally of the wings. These shutters 27 are to be manipulated by any suitable means from the cockpit of the craft to either increase or decrease the effective area of the 90 radiator according to the needs of the motor. In extremely cold weather or in high altitudes the shutters 27 are slid inwardly to cover a portion of the radiator surface ordinarily effective to thus simultaneously decrease the cooling effect and increase the lifting efficiency of the wings by reason of the increased supporting surface area. The shutters preferably underlie that portion of the wing surface remote from the fuselage 100 to work inwardly so that the radiator section directly adjacent the fuselage will be the last section covered. Obviously as the wing surfaces approach the fuselage an appreciable decrease in lift is caused by the 105 interference of the fuselage with the flow of air. Guides 28 overlap the fore and aft edges of the shutters which are curved or cambered slightly to complement the wings.

It is to be understood that the basic idea 110 here involved is the construction of the radiator in substantially aerofoil form or in a form substantially horizontally flat for translation through the air edgewise to offer a minimum of resistance without decreased cooling efficiency. The radiator may of course, be made as a unit and placed directly above the fuselage, or in fact at any point within either supporting surface. It may be extended beyond the wing beams of the 120 wings, or it may be extended slightly above the plane of the top surface of the wing without departing from the spirit of the invention claimed. In other words it is to be understood that no limitation is intended 125 except in so far as the claims compel.

What is claimed is:

1. A substantially horizontally flat radiator for aeroplanes comprising a plurality of radiator sections of substantially aerofoil 130

- form together with means for directing the air stream over the side walls of the radiator sections when the radiator is translated edge-wise through the air.
5. A substantially horizontally flat radiator for aeroplanes of approximately aerofoil form together with means movable relatively to it for regulating the air flow through the radiator parts, the radiator, by reason of its construction exerting some useful lift, the extent of the lift being variable by adjustment of said movable means.
10. 3. A substantially horizontally flat radiator for aeroplanes of approximately aerofoil form in combination with means movable relatively to it for simultaneously lessening the radiating efficiency of the radiator and increasing the dynamic lift or vice versa.
15. 4. A radiator for aeroplanes comprising a plurality of spaced radiator sections of substantially aerofoil form having air passages extending transversely through them, the ends of the air passages being open to the air space between the radiator sections.
20. 5. A radiator for aeroplanes comprising a plurality of laterally spaced longitudinally extending radiator sections having transverse air passages formed in them together with means between the sections arranged to provide upwardly and rearwardly inclined air passages.
25. 6. A radiator for aeroplanes comprising a plurality of laterally spaced longitudinally extending radiator sections of substantially aerofoil form (viewed from the side), the arrangement of the sections being such that air is permitted to pass transversely between them without nullifying completely the dynamic lift efficiency of the radiator as a whole.
30. 7. The combination with a radiator for aeroplanes of substantially aerofoil form, of means for regulating the quantity of air passing through it.
35. 8. A radiator for aeroplanes comprising a plurality of longitudinally extending radiator sections having spacers arranged between them to extend angularly upwardly and rearwardly.
40. 9. A radiator for aeroplanes comprising a plurality of longitudinally extending radiator sections of substantially aerofoil form, headers common to the several sections, transverse air passages formed in said sections, and spacers arranged between said sections for holding them in parallelism.
45. 10. A radiator for aeroplanes comprising a plurality of laterally spaced longitudinally extending radiator sections, transversely extended headers common to the several sections, and spacers providing air passages between said sections.
50. 11. A radiator for aeroplanes comprising a plurality of radiator sections of substantially aerofoil form, headers common to the several sections, and spacers arranged between said sections to provide air passages, the spacers being upwardly and rearwardly inclined from the underneath surface of the radiator.
55. 12. A radiator for aeroplanes comprising a plurality of radiator sections of substantially aerofoil form, transverse air passages formed in the radiator sections, headers common to the radiator sections, and spacers for the radiator sections providing angular air passages between them.
60. 13. A radiator for aeroplanes comprising longitudinally separated headers, radiator sections interconnecting the headers, and an expansion tank common to both headers.
65. 14. In an aircraft, the combination with a supporting surface, of a radiator of substantially aerofoil section mounted in continuation of said surface without interrupting the continuity of the structural elements thereof, the said radiator comprising a plurality of radiator sections appropriately spaced to increase the effective radiation surface.
70. 15. In an aircraft, the combination with a supporting surface, of a radiator built into said surface as an integral part thereof and in a manner such that air is permitted to pass transversely through the supporting surface to increase the cooling efficiency of the radiator.
75. 16. In an aircraft, the combination with a supporting surface, of a radiator of substantially aerofoil section built into said surface, said radiator comprising a plurality of laterally spaced radiator sections, the exterior lines of which are such that the continuity of the exterior surface of the supporting surface is uninterrupted throughout.
80. 17. In an aircraft, the combination with a supporting surface, of a radiator of substantially aerofoil section mounted in continuation of said surface with its section of maximum thickness coincident with the center of pressure of said surface.
85. 18. In an aircraft, the combination with a supporting surface, of a radiator of substantially aerofoil form built into an opening in the supporting surface to continue the exterior form of said surface uninterruptedly, together with means for varying the size of said opening to cut down the effective area of the radiator and simultaneously increase the lifting efficiency of the supporting surface or vice versa.
90. 19. In an aircraft, the combination with a supporting surface, of a radiator of substantially aerofoil form mounted in an opening formed in said supporting surface, and means for varying the effective area of the radiator by altering the size of said opening.
95. 20. In an aircraft, the combination with a supporting surface, of a radiator of substantially aerofoil section mounted in continu-

ation of said surface with its area of maximum radiation substantially coincident with the center of the pressure thereof.

21. In an aircraft, the combination with a fuselage having aeroplane wings extended laterally from it in the plane of the top thereof, of radiators mounted in said wings closely adjacent the fuselage, the placement of the radiators being such that the air ordinarily confined within the angles formed between the fuselage and wings will escape through the radiators.

22. In an aircraft, the combination with a supporting surface, a radiator built into said surface, and means for varying the effective area of the radiator to either increase or decrease the lifting efficiency of said surface.

23. A radiator for airplanes of substantially aerofoil section having air passages

extending transversely through it, the air 20 passages being generally inclined rearwardly and upwardly from the underneath face of the radiator.

24. A substantially horizontally flat radiator for airplanes having transversely extending air passages formed in it, the arrangement of the air passages being such that air is forced through them as the radiator is translated bodily edgewise through the air, said radiator from front to rear being generally inclined to present, during its translation through the air, an angle of incidence conducive to some useful lift.

In testimony whereof we hereunto affix our signatures.

WILLIAM L. GILMORE.
